Attorney:

UNITED STATES PATENT OFFICE.

FREDERIC MARTIN, OF COLUMBUS, OHIO.

CORN-HUSKING TOOL.

Application filed May 22, 1922. Serial No. 562,761.

To all whom it may concern:

Be it known that I, FREDERIC MARTIN, a citizen of the United States, residing in Columbus, in the county of Franklin, State 5 of Ohio, have invented certain new and useful Improvements in Corn-Husking Tools, of which the following is a specification.

This invention relates to an improved appliance which is constructed and adopted to 10 be worn in the palm of an operator's hand for the purpose of facilitating the husking of corn.

Among the objects of the invention are: The provision of an improved appliance of 15 this nature which consists of a metallic claw member and a base structure by which the appliance is removably secured in the palm of the hand, and wherein an improved flexible connection is provided between the claw 20 member and base structure to admit of swinging movement of the claw member by finger pressure so that the sharpened end thereof may be directed and forced into the foliage encasing of the vegetable; in the 25 provision of an improved connection between the claw member and base structure by means of which the claw member may be longitudinally adjusted to adapt the same more perfectly to the operator's hand, there- 30 by enabling the device to be employed by many different users, and the invention fur- 35 ther consists in other improved details of construction which will be apparent to those versed in the art by perusal of the following description, particularly when the latter is read in connection with the accompanying drawing.

In said drawing—

Figure 1 is a perspective view of my im- 40 proved corn husking device.

Figure 2 is a horizontal sectional view taken through the device on the line 2—2 of Figure 1.

Figure 3 is a transverse vertical sectional 45 view on the line 3—3 of Figure 1.

Figure 4 is a detail view of the claw mem- 50 ber.

Figure 5 is a similar view of the base structure.

Referring more particularly to the details 55 of the invention, the numeral 1 designates my improved device in its entirety, the same constituting particularly many specific structural improvements in the struc-

ture disclosed in my co-pending application, 55 Serial Number 455,587 filed March 25, 1921, and patented Dec. 26, 1922, No. 1,440,164.

Broadly, the device consists of a base sec- 60 tion or structure 2 and a claw member 3. In this instance the base structure is formed from a blank of sheet metal bent to comprise inner and outer layers 4 and 5 respec- 65 tively. These layers are curved vertically to easily and naturally conform to the shape of the hand, the said layers terminat- 70 ing in curved extremities 6 and 7, the former of which being arranged, when applied, to pass over the margin of the operator's palm immediately in advance of the thumb, and the extremity 7 engages the under part of 75 the palm, as shown. Preferably these layers are maintained in contiguous engagement by rivets 8. In bending the blank of the base section, the latter is formed to in- 80 clude spaced hinge ears 9, disposed imme- 75 diately adjacent the rivets 8 and adapted to receive a pintle 10, by means of which there is hinged to the base a claw holder 11. This holder is, also, formed from a blank of sheet metal and is bent upon itself to include 85 spaced layers 12 and 13 having the edges thereof recessed or notched as at 14. The layers 12 and 13 are provided with register- 90 ing openings through which pass the thread- 85 ed shanks of bolts 25, the latter being each headed at one end and arranged to receive a binding nut 15 at the other.

Disposed between the layers 12 and 13 and arranged to be adjustably clamped therebetween is a metallic claw member 16, 90 which is formed to include a substantially curved outer end 18, which is sharpened and upon manipulation is adapted to be brought into penetrating engagement with the foliage covering of corn ears so as to 95 tear such foliage loose from its normal position and thereby facilitate the task of corn husking.

It will be observed that when the device 100 is applied the claw member will be situated so as to extend lengthwise of the operator's fingers and since the claw member is hinged to the base structure, it follows that by finger pressure the claw member may be flexed to engage the foliage of the corn 105 when the latter is grasped by the operator preparatory to the husking operation. It will be noted that the tool may be manip-

ulated in a normal and natural manner closely conforming to the ordinary operation of husking by hand, and it is this fact that greatly contributes to the usefulness of the tool and expedites output. The claw member is positively secured to the holder 11 by slotting the end 17 thereof longitudinally as at 19. This slot receives the bolts and since the end 17 is inserted 10 between the layers 12 and 13 of the holder, it follows that when the nuts 15 are tightened the claw may be maintained in various longitudinal positions of adjustment with respect to the holder and the base structure. 15 This feature of adjustment is of primary importance in adapting the tool to the hands of different users, and in enabling the claw to be operated most effectively.

To removably secure the tool in place, I 20 provide the curved ends of the base extremities 6 and 7 with eyes 20 to which are pivotally secured links 21 carrying an adjustable elastic strap 22, which fits over the back of the hand and exercises a sufficient 25 tension to maintain the tool in its applied position. Also, the claw member is provided with slots 23 in the end 17 thereof, which slots register with the recesses 14 and receive a strap 24 disposed to fasten about 30 the operator's fingers in order that the claw member will be at all times in engagement with the fingers and, therefore, instantly

responsive to all operative movements, no matter how positive, forceful or sensitively directed.

35

In view of the foregoing it will be seen that the present invention provides a corn husking appliance of substantial, practical and improved construction which readily adapts itself to economical manufacture and efficient operation, and by its construction the appliance is rendered adaptable, by the production of a single size, to the hand of anyone, dispensing therefore, with a multiplicity of sizes, heretofore deemed necessary.

40

45

I claim:

1. In a corn husking tool, a sheet metal base strip formed to include inner and outer integral layers, eyes formed with said layers, a claw holder of sheet metal bent to provide integral inner and outer layers, the latter being integrally joined by an eye portion arranged to register with the eyes of said base strip, a pin passing through said eyes to flexibly unite said strip and holder, and a claw member secured between the inner and outer layers of said holder.

50

55

2. A structure as specified in claim 1 and wherein the claw member is connected for longitudinal adjustment with said holder.

60

In testimony whereof I have signed my name to this specification.

FREDERIC MARTIN.
